US00D614523S

(12) **United States Design Patent**
Rabassa et al.

(10) **Patent No.:** US D614,523 S
(45) **Date of Patent:** ** Apr. 27, 2010

(54) **WATCH DIAL**

(75) Inventors: **Serge Rabassa**, Geneva (CH); **Sophie Boulangeot**, Geneva (CH)

(73) Assignee: **Cartier Creation Studio SA**, Geneva (CH)

(**) Term: **14 Years**

(21) Appl. No.: **29/337,694**

(22) Filed: **May 28, 2009**

(51) LOC (9) Cl. **10-07**

(52) U.S. Cl. **D10/126**

(58) Field of Classification Search D10/122-126, D10/30-39; 368/28, 80, 223, 228, 232

See application file for complete search history.

Primary Examiner—Lucy Lieberman

(74) Attorney, Agent, or Firm—Kalow & Springut, LLP; Scott D. Locke, Esq.

(57) **CLAIM**

The ornamental design for a watch dial, as shown and described.

DESCRIPTION

The sole view is a front elevation of a watch dial showing the new design.

The broken lines are for illustrative purposes only and form no part of the claimed design.

1 Claim, 1 Drawing Sheet
